UNITED STATES PATENT OFFICE

ALBERT M. LIVELSBERGER, OF FORT WAYNE, INDIANA.

DRAFT-EQUALIZER.

SPECIFICATION forming part of Letters Patent No. 355,184, dated December 28, 1886.

Application filed November 2, 1886. Serial No. 217,775. (No model.)

To all whom it may concern:

Be it known that I, ALBERT M. LIVELSBERGER, of the city of Fort Wayne, county of Allen, and State of Indiana, have invented 5 certain new and useful Improvements in Draft Equalizers, of which the following is a specification.

My said invention relates to that class of equalizers whereby two pairs of horses, one arranged in front of the other, may be compelled 10 to pull equally upon the load.

Said invention principally consists in the connecting of the two double-trees (rear and front) by a rope or chain passing over a pulley or pulleys at the rear end of the tongue, as will be hereinafter more particularly described and claimed.

It further consists in providing in the same apparatus a means of giving the rear double-tree an elastic movement when the front one (together with the team attached thereto) is not used, also as will be hereinafter more particularly described and claimed.

Referring to the accompanying drawings, 25 which are made a part hereof, and on which similar letters of reference indicate similar parts, Figure 1 is a top or plan view of a tongue and the two sets of double-trees and single-trees embodying my said invention; Fig. 2, a 30 central vertical section of the same on the dotted line 2 2 in Fig. 1; Fig. 3, a detail sectional view on an enlarged scale, similar to a portion of Fig. 2; Fig. 4, a transverse vertical sectional view, looking toward the left from the dotted line 4 4 in Fig. 3; Fig. 5, a view similar to Fig. 35 1, but showing a somewhat different construction, in which two pulleys instead of one are employed; and Fig. 6, a side elevation of the same.

40 In said drawings, the portions marked A represent the tongue; B, the rear double-tree; C, the front double-tree; D, the pulley or pulleys at the rear end of the tongue, over which the connecting rope or chain passes; E, said 45 connecting rope or chain, and F a spring by which the elastic movement of the rear double-tree is secured when it is the only one employed, as before mentioned.

The pole or tongue A is, in the main, an ordinary tongue to a wagon, engine, machine, or whatever it may be desired to draw. I may

here say that this invention has been used most commonly with the machines known as "road-scrapers;" but of course it may be used wherever teams are employed as a means of draft. 55

The rear double-tree, B, carries the usual single-trees, as shown, and is in the main of the ordinary construction. It is adapted, however, to slide back and forth on the tongue A, and this may be accomplished either by mounting 60 it in ways secured to said tongue, as shown in Figs. 1, 2, 3, and 4, or it may be mounted in a slide which surrounds said tongue, as shown in Figs. 5 and 6, it being only essential that it shall be capable of sliding back and forth, and 65 not essential how the slide shall be constructed.

The pulley or pulleys D are located at the rear end of the tongue, and are mounted on a shaft secured in bearings therein. The rope or chain E passes over this pulley, and thus 70 an absolutely equal chance is given each of the teams, as the relative force is not varied by a changing of the position of the double-trees, as is the case where levers or such like devices are employed, which, I am aware, has been 75 done, and which I desire now to expressly disclaim. This rope or chain E is shown as a rope only for a sufficient distance to afford the desired flexibility to pass around the pulley, the greater part of the connection being shown as 80 a rod; but it is obvious that it might be a rope for the whole distance or a chain without departing from my invention, that portion of it which remains always substantially straight being either stiff or flexible, as may be desired 85 by the maker or user. Rods are used for these straight portions, because they are somewhat more convenient and less expensive; but they are a mere continuation of the rope for the purposes of this invention, and are so considered. 90

The spring F is located in a barrel, F', secured to the under side of the tongue A. Ordinarily, when both teams are employed, this spring exercises no function, as the rod or rope 95 passes directly through it. However, when the front double-tree, C, is removed and only one pair of horses is employed, a pin, e, is passed through a hole formed to receive it in an enlarged or flattened portion of the rod, which passes through this spring; but in case the rope 100 is continued through, then a metal link may

be inserted at this point for the purpose. A small cap or washer, *f*, is usually provided, which covers the end of the spring and serves as a bearing for this pin. Thus, (the spring 5 being seated in the bottom of the barrel,) when the horses pull upon the double-tree, the spring yields somewhat, and, instead of a dead pull, the elastic movement desired is attained, as well as a very simple means of securing this double-tree in position, for the purpose mentioned. The rod or rope is supported at its forward end 10 by a link, *a*, attached to the under side of the tongue.

The front double-tree, *C*, and the whiffletrees 15 attached thereto are of the usual construction, and are only shown to illustrate the operation of this invention.

Having thus fully described my said invention, what I claim as new, and desire to secure 20 by Letters Patent, is—

1. The combination, in a four-horse equalizer, of a tongue having pulley or pulleys at its rear end and provided with a slide or ways, a rear double-tree mounted in or upon said 25 slide or ways on said tongue, a front double-

tree, and a rope or chain passing over said pulley or pulleys and connecting said rear and front double-trees, substantially as shown and described.

2. The combination, in a draft-equalizer 30 arranged for two pairs of horses, one in front of the other, in which the front double-tree and pair of horses may be attached to the rear double-tree mounted in or upon ways or slide on the tongue of said rear double-tree, of a spring, 35 also secured to said tongue, a rope or chain passing from said double-tree over a pulley through said spring, and a pin, *e*, by which said rope or chain can be secured to said spring, whereby an elastic movement may be imparted 40 to said double-tree when thus used alone, substantially as set forth.

In witness whereof I have hereunto set my hand and seal, at Fort Wayne, Indiana, this 25th day of October, A. D. 1886.

ALBERT M. LIVELSBERGER. [L. S.]

In presence of—

CHAS. F. PFEIFFER,
ARTHUR FITZSIMONS.
